DOFFING AND DONNING APPARATUS FOR TEXTILE MACHINES

James F. King, Jr., and Donald A. Sloan, Winston-Salem, N.C., assignors to The Bahnson Company, Winston-Salem, N.C., a corporation of North Carolina
Filed June 14, 1963, Ser. No. 287,819
27 Claims. (Cl. 57—53)

This invention relates to an improved doffer-donner machine by means of which full bobbins along a line of spindles on a textile processing machine such as a spinning frame or the like are doffed in succession as the machine proceeds longitudinally along the line of spindles, and empty bobbins are donned in succession on the spindles from which the full bobbins have just been removed, the doffing and donning operations proceeding automatically and without any requirement for attention of the operator once the doffer-donner machine has been installed at one end of the spinning frame and set into operation.

A principal object of the invention is accordingly to provide an improved doffer-donner machine wherein the doffing and donning operations take place in an expeditious manner without requiring any manual handling of the bobbins.

Another object is to provide an automatically operating doffer-donner machine which can be wheeled from one textile machine to another and easily installed on and removed from the textile machine.

A further and more specific object of the invention is to provide an improved doffer-donner machine in which the doffer and donner units are supported by a structure that is carried on a truck base, the support structure and therefore also the doffer and donner units being adjustable vertically with respect to the truck base so that the doffer and donner units may be raised to the necessary height to install the entire doffer-donner machine on a rail for movement longitudinally of the textile machine, the truck base then being drawn upwardly so as to clear the floor.

Another object of the invention is to provide an improved doffer-donner machine in which various operating components of the doffer and donner units can be shifted between an operating position relative to the spindle line and a retracted position so as to protect these components against possible damage.

A further object is to provide an automatically operating doffer unit on a doffer-donner machine which includes an improved arrangement for transferring the full bobbins as they are removed from the spindles to a bobbin box and depositing the bobbins in a properly oriented manner in the box.

A further object is to provide an improved arrangement for handling the full bobbins after being doffed, the handling mechanism including a guide hood above the spindle line into which the bobbins are injected from their spindles, a transfer mechanism receiving the bobbins from the guide hood, this transfer mechanism including an arrangement for orienting the bobbins and passing them to the inlet end of a pivotally mounted loader conveyor, and the bobbins being discharged from the loader conveyor into a suitable receptacle.

Still another object of the invention is to provide an improved donner unit of a doffer-donner machine which includes a magazine for storing a relatively large number of empty bobbins in a plurality of feed channels, a conveyor of the endless type associated with the discharge ends of the feed channels in the magazine for transferring the empty bobbins from the magazine to a donner head located at the discharge end of the conveyor, the empty

2

bobbins being discharged from the donner head onto the spindles as the donner head passes along the line of spindles.

A further object is to provide an improved donner unit of a doffer-donner machine which is pivotally mounted and automatically controlled as to position so that the donner head from which the bobbins are discharged is always in correct alignment with the upper end of the spindle thereby assuring accuracy in placing the bobbins on the spindles.

The foregoing as well as other objects and advantages inherent in the invention will become more apparent from the following detailed description of one main embodiment of the improved doffer-donner machine together with certain modifications for the doffer and donner units, and from the accompanying drawings. In these drawings:

FIG. 1 is a front elevation of the entire doffer-donner machine;

FIG. 2 is a rear elevation of the entire doffer-donner machine;

FIG. 3 is an end elevation of the entire doffer-donner machine;

FIG. 4 is a vertical section on line 4—4 of FIG. 3;

FIG. 5 is an enlarged section on line 5—5 of FIG. 3;

FIG. 6 is a partial side elevation of the machine showing the manner in which the full bobbin loader mechanism operates;

FIG. 7 is an enlarged side detail view of part of the doffer unit and related guide hood;

FIG. 8 is a vertical section on line 8—8 of FIG. 1 showing the guide hood for the full bobbins together with the mechanism by which the hood is retracted;

FIG. 9 is an enlarged detail of the support rail attached to the spinning frame on which the entire machine is supported for movement longitudinally along the frame;

FIG. 10 is a view in elevation of the donner unit as would be seen when looking in the direction of the arrow in FIG. 2, the view being drawn to an enlarged scale;

FIG. 11 is a side elevation of the donner unit as seen in the direction of the arrow in FIG. 10;

FIG. 12 is a vertical transverse section of the donner unit on lines 12—12 of FIG. 10;

FIGS. 13, 14 are sectional details on lines 13—13, 14—14, respectively of FIG. 12;

FIG. 15 is a horizontal section of the donner unit on line 15—15 of FIG. 12;

FIG. 16 is a horizontal section of the donner unit on line 16—16 of FIG. 11;

FIG. 17 is a perspective view of the magazine for empty bobbins when detached from the donner unit;

FIG. 18 is a top plan view of the torsion spring drive mechanism for actuating the rotatable driver shaft by means of which empty bobbins are transferred in succession from the delivery conveyor on the donner unit to the donner head from which the bobbins are discharged in succession onto the spindles;

FIG. 19 is a vertical section on line 19—19 of FIG. 18;

FIG. 20 is a bottom plan view of a lock-up mechanism by means of which the driver shaft is permitted to rotate periodically in steps of 180°;

FIG. 21 is a schematic circuit diagram showing the electrical control circuit for the entire machine;

FIG. 22 is a view showing the arrangement for the pneumatic cylinders by means of which the doffer and donner units are raised and lowered relative to the truck base on which they are supported;

FIG. 23, 23a combined is a view in side elevation of a modified construction for the bobbin guide hood and related transfer chute for delivering full bobbins to the loader conveyor;

FIGS. 24, 24a combined is a vertical section on line 24—24 of FIG. 23;

FIG. 25 is a section on line 25—25 of FIG. 23 showing the shelf-closing doors at the entrance to the guide hood;

FIG. 26 is a side elevation of a modified construction for the donner head;

FIG. 27 is an end elevation of the donner head shown in FIG. 26;

FIG. 28 is a horizontal section on line 28—28 of FIG. 26;

FIG. 29 is a perspective view of a hold-down device which can be included on the machine for holding each spindle in place against upward movement as the upward doffing force is applied to the bobbin;

FIG. 30 is a view in side elevation of the spindle hold-down device;

FIG. 31 is a horizontal section on line 31—31 of FIG. 30;

FIG. 32 is a partial rear elevation similar to FIG. 2 showing a modification providing automatic control over the movement of the guide hood and bobbin lifter arm and donner structure at the head and foot ends of the textile machine;

FIG. 33 is a vertical section similar to FIG. 8 showing the modifications related to FIG. 32;

FIG. 34 is a longitudinal elevation of the textile machine showing the arrangements provided at the head and foot ends for effecting the automatic control of the doffer and donner components; and

FIG. 35 is a circuit diagram similar to FIG. 21 showing the modifications in the electrical controls essential for automatic operation of the modified construction according to FIGS. 32—34.

General

With reference now to the drawings and to FIGS. 1—4 in particular, the doffer-donner mechanism, because of its relatively large mass, and in the interest of making it mobile, is preferably mounted on a truck base to enable it to be easily pushed about the spinning room from one spinning frame to another. The truck base comprises a horizontal rectangular base plate 10 and extending downward from this plate are spaced bearing housings 11 at one end of the plate which receive rigid axles 12 on which wheels 13 are mounted. At the opposite end of plate 10 are two other spaced wheels 14 and these are arranged on casters 15 so as to enable the truck to be maneuvered easily in any direction so as to come into the proper position alongside the spinning frame which is to be doffed.

Upstanding at each rear corner of the base plate 10 is a profiled channel 16 and these channels serve to guide the doffer-donner assembly as it is raised and lowered relatively to the truck base so as to enable the entire machine to be mounted on the spinning frame for travel along the line of bobbins B to be doffed.

The doffer-donner assembly includes a vertically disposed mounting plate 17 and extending vertically along each side of this plate is an angle-iron 18 suitably secured to the inner face of the plate. A plurality of vertically spaced studs 19 extend laterally outward from each angle iron into the corresponding profiled channel 16 and these studs serve as shafts for mounting guide rollers 20 thereon which establish a guiding contact with the interior wall of the channel. Inverted L-shaped brackets 21 secured to the inner face of mounting plate 17 serve to support a horizontally extending platform 22 on which is placed a bobbin box 23 to receive the full bobbins B as they are doffed in succession from the line of spindles.

Mounting plate 17, together with all of the doffer-donner components is raised and lowered relative to the truck base 10 by two parallel spaced pneumatic power units of the double-acting piston and cylinder type. The upper end of each cylinder 24 is secured by a clevis pin

25 to a lateral projection from the upstanding angle iron 18, and the lower end of each piston rod 26 is secured by a clevis pin 27 to the truck base plate 10. Thus, the truck base plate 10 and the mounting plate 17 for the doffer-donner operating components can be raised and lowered relative to each other by admitting compressed air into one end or the other of each cylinder 24 by means of a manually operated 3-way control valve 28 secured to one side of plate 17. As shown in FIGS.

10 4 and 22, as control handle 29 for valve 28 is rotated in one direction, compressed air from a source (not illustrated) and connected through a hose 30 to a nipple 32 on the housing for valve 28 is passed through the valve and through flexible hose line 33 to the top of each cylinder 24 to thus cause the piston rods 26 to be ejected from the cylinders as the pistons 26a within the cylinders are displaced downward. Air from the lower ends of cylinders 24 is exhausted through hose lines 34 and through valve 28 to the atmosphere. When control handle 29 is rotated in the opposite direction, compressed air is admitted through hose lines 34 to cause the pistons and piston rods to be shifted in the opposite direction so as to move upward in cylinders 24 and air is exhausted from the upper ends of cylinders 24 and through hose lines 33 and valve 28. A variable flow constrictor device 35 can be placed in the hose line 33 before it branches to the two cylinders 24 so as to control the speed at which the pistons and piston rods 26 are displaced in their cylinders 24.

30 For propelling the doffer-donner machine along the spinning frame, a drive motor M1 is mounted on the inner face of the vertical support plate 17. Through reduction gearing, motor M1 drives a sprocket 36 which is connected by a vertical chain 37 to an upper sprocket 38 secured upon a shaft 39 which extends through plate 17. Secured to shaft 39 at the outer face of plate 17 are a rear driving sheave 41 and a second sprocket 42 which is connected by a horizontal chain 43 to a front sprocket 44 secured upon shaft 45 to which is also secured 40 a front driving sheave 46. The rear and front driving sheaves 41, 46 are adapted to be placed on a horizontal track rail 47 extending longitudinally of and secured to the spinning frame F and hence, as motor M1 operates, the rear and front sheaves 41, 46 will be driven thus to 45 propel the doffer-donner machine along the spinning frame. A guide wheel 40 rotatably mounted at the bottom of plate 17 is adapted to engage a lower guide rail 60 on the frame. Thus, the two driving sheaves 41, 46 in cooperation with guide roller 40 below them provide a three point support to maintain the doffer-donner machine in a vertical position during its travel along the frame.

Secured upon shaft 45 at the inner side of plate 17 is a gear 48 which meshes with gear 49 secured upon a jackshaft 50 on which is mounted a sprocket 51 that drives a horizontal chain 52 and sprocket 53 secured upon a shaft 54 that serves to pivotally support and drive an endless conveyor type of full bobbin loader 55 which serves as one component of the overall transfer mechanism by which full bobbins as they are doffed in succession from the frame spindles 76 are loaded into the bobbin box 23. This loader mechanism will be described later in further detail.

Drive motor M1 and all other components which require electrical power are arranged to be energized from a horizontal bus bar 56, see FIGS. 2, 9 and 21, which also extends longitudinally along the spinning frame F at a level somewhat lower than the track rail 47. For taking off power from bus bar 56, a brush block assembly 57 is utilized, this being secured upon an arm 58 that is pivotally mounted on a vertical shaft 59 for rotation about the shaft axis. A push button type of switch SW5 which functions to periodically energize the magnet 62 which actuates the doffer mechanism to be later described, is also secured upon a similar arm 63 directly

above arm 58 and which is likewise mounted pivotally on the vertical shaft 59.

The brush block assembly 57 and switch SW5 are adapted upon pivotal movement of their support arms to move in and out through an aperture 64 in plate 17. These two components are preferably retracted automatically to a position preferably at least flush with the outer face of plate 17 before the doffer-donner machine is mounted upon rail 47 and are similarly automatically extended into their respective operative positions after the drive sheaves 41, 46 have been mounted upon rail 47 and the truck base 10 elevated to its off-the-floor position which is the position shown in the drawings. The mechanism for accomplishing this is comprised of a cam plate 65 which is pivotally mounted upon the inner face of plate 17 and a cam follower roller 66 carried by the lower arm 58. The two arms 58, 63 are mechanically coupled by a bar 67 secured to the upper arm 63 and which engages the face of arm 58, and a torsion spring 68 on shaft 59 places a torque on this arm tending to rotate it in such direction as to cause this arm and the lower arm coupled to it to move switch SW5 and brush block assembly 57 outward through aperture 64 to their operative positions.

Cam plate 65 is arranged to be actuated by a mechanical linkage comprising a rod 69 which is articulated at its opposite ends respectively to cam plate 65 and to one arm 71a of bellcrank lever 71 mounted pivotally at the inner side of plate 17. The outer end of the other lever arm 71b is arranged to lie in the path of a detent 72 secured to channel 16, the arrangement being that as the truck base 10 is raised off the floor by retracting piston rods 26 within their cylinders 24, bellcrank lever 71 will be rotated clockwise as viewed in FIG. 4, thus, also rotating cam plate 65 clockwise. In this direction of movement, cam follower roller 66 shifts in such direction as to permit the two coupled and spring-loaded arms 58, 63 to move switch SW5 and the brush block assembly 57 into their operative positions. When truck base 10 is lowered relative to plate 17, detent 72 will also lower and disengage lever 71 thus permitting the latter and cam plate 65 to rotate counterclockwise under a restoring force established by tension spring 73, one end of this spring being anchored and the other end being secured to cam plate 65. This movement serves to rotate arms 58, 63 in the opposite direction so as to retract switch SW5 and brush block assembly 57 to their inner, inoperative positions. In their extended, operative positions brush block assembly 57 engages bus bar 56, and switch SW5 is then so located as to be actuated periodically by a series of bosses 74 on track rail 47, see FIGS. 9 and 21, these bosses having the same spacing and essentially the same location as the spindles 76 of the spinning frame so that the doffer mechanism will be periodically actuated at each spindle location so as to drive the full bobbin B thereon in the upward direction.

Doffer unit

The doffer unit includes the solenoid 62 previously described which is energized periodically by closure of the contacts of switch SW5 as the latter periodically engages the spaced bosses 74. As shown in FIG. 7, each time that solenoid 62 is energized, it causes rod 77 attached to the solenoid armature to move upwardly and compress spring 78, the potential force stored in this spring by its compression being applied against the under side of lever 79 which is initially latched against movement. When rod 77 reaches a pre-determined position, a lateral projection 77a rotates a latch lever 81 counterclockwise thus releasing latch roller 82 from a notch 83 in lever 79 whereupon the latter is released for movement upwardly at high acceleration by the suddenly released force stored in the compressed spring 78. A roller 84 at the end of lever 79 engages the underside of a pivotally mounted lifter arm 85, the outer end 85a of this lever being adapted to engage either beneath the

butt end of a full bobbin B as shown in FIG. 7 or against the lower tapered part of the thread package on the bobbin, and hence, lifter arm 85 is likewise accelerated upwardly so as to drive the bobbin upwardly with sufficient acceleration to clear spindle 76 and enter a receiving or guide hood 86 which constitutes the first step in the procedure for transferring the full bobbins as they are doffed in succession from the spindles 76 into the bobbin box 23.

The details of the bobbin lift-off mechanism are more fully disclosed and claimed in a co-pending application, Serial No. 83,418, filed January 18, 1961, now Patent No. 3,148,495.

Solenoid 62 and all of the lever mechanisms described above in association with operation of the lifter arm 85 are carried by and between a pair of parallel spaced, vertically extending side plates 87. The hood 86 which has a top arcuate wall to guide the bobbins B on their way to the bobbin box is mounted between the upper ends of the side plates 87 for movement between an operative position over the line of bobbins on the spinning frame, and a retracted position essentially flush with the front edges of plates 87 so as to clear any obstruction that might exist at the end of the frame when the doffer-donner machine reaches this point, thereby protecting the hood against damage. A thread guide 86a is attached to the front of hood 86 to keep the threads from being snagged and broken. Hood 86 is biased by a spring 89 so as to move automatically to its forward, operative position when it is released from its latched-in retracted position. As seen in FIG. 8 a bellcrank lever 88 mounted on the outer face of one of the side plates 87 has one arm 88a pivotally connected to the lower, forward part of hood 86 and the arcuate plate spring 89 is attached to the upper rear part of the hood. Spring 89 serves to move the hood forward to its operative position, the position shown in the drawings, whenever bellcrank lever 88 is released from its latching lever 91 which is also pivotally mounted at one end on the outer face of side plate 87. Latching lever 91 includes a notch 91a to receive a latch pin 92 on lever arm 88a. Connected to the other lever arm 88b is a wire cable 93 extending downwardly and then horizontally around a guide pulley 94 shown in FIGS. 1 and 4 to a terminal connection at one arm 95a of a rock shaft 95 which is journaled in a support bracket 96 upstanding upon base plate 10 and extends through support plate 17. The other arm 95b at the outer face of support plate 17 terminates in a cam follower roller 97 seen in FIG. 2 which is adapted to be actuated by a cam surface, not shown, provided at the end of the spinning frame. As shaft 95 is rocked counter-clockwise, as viewed in FIG. 1 upon striking the cam surface, a downward pull is exerted upon cable 93 thus rotating lever 88 clockwise as viewed in FIG. 8 and causing hood 86 to shift to its retracted position and to be latched to its latching lever 91. The hood will remain in this retracted position until manually released after the doffer-donner machine has been set up at the end of another frame which is ready to be doffed and donned. The manual release mechanism shown in FIGS. 4, 5 and 8 includes a crank rod 98 which terminates at one end in a crank handle 99. The crank rod 98 also includes a crank arm 100 which is connected by linkage 101 to latch lever 91 so that as handle 99 is rotated, latch lever 91 will be shifted pivotally downward, overcoming the force of its biasing spring 102 thus releasing latch pin 92 to permit hood 86 to move forward to its operating position.

Lifter arm 85 of the doffer mechanism is also mounted so as to shift between a forward, operative position for doffing and a retracted position where it will escape damage from any obstruction at the frame end. As shown in FIG. 7 lifter arm 85 is articulated to one arm 103a of a double arm lever 103. The other lever arm 103b is connected to one end of a tension spring 104 and is

actuated by a rocker arm 105 on rock shaft 106, the bell-crank lever 88 also being secured upon this shaft. Thus, when lever 88 is rotated in the direction such as to shift hood 86 to its forward position, the simultaneous rotary movement of rock shaft 106 and rocker arm 105 will cause lever 103 to shift lifter arm 85 to its forward, operative position. Conversely, when lever 88 is rotated in the opposite direction to retract hood 86, so also will lifter arm 85 be retracted.

Full bobbins B are discharged from the hood longitudinally of themselves onto an endless transfer belt assembly shown in FIGS. 1-5 which comprises two V-belts 107 arranged side-by-side the belts being mounted on sheaves 108, 109 which are secured upon shafts 111, 112 respectively. One of these shafts, such as shaft 111, is driven by a motor M2 through drive sprocket 113 on the motor shaft, chain 114 and sprocket 115 secured upon shaft 111. Sheaves 109 and shaft 112 are mounted at a slight dip angle from the horizontal thus giving the belts a slight twist sideways which dips downwardly to facilitate roll-off removal of the bobbins from the belt.

The bobbins are moved along belts 107 for a short distance until they reach a position in alignment with a transition chute 116 shown best in FIG. 5 having a zig-zag configuration. At this point, the full bobbins B leave the belt by a movement generally parallel to themselves as they are deflected by a curved wall 116b of chute 116 and enter the upper end of chute 116. The bobbins then drop in the chute parallel to themselves in two stages and reach the lower discharge end at which they are now removed in succession by a lever type plunger 117. Chute 116 serves not only to straighten out the bobbins but also to decelerate them. As seen in FIG. 5, the head 117a of plunger 117 projects through an aperture 116a in the wall of chute 116 and is adapted to be shifted back and forth to effect discharge of the bobbins in succession. When the head 117a of this lever occupies the position shown in FIG. 5, the lowermost positioned bobbin in chute 116 rests on the upper side thereof. When head 117a is retracted from the chute, the lowermost bobbin is allowed to drop into the discharge position in front of the end face of the head, and when the head moves forward, it pushes that bobbin into the receiving end of the loader conveyor 55. The back and forth movement of lever plunger 117 is obtained by means of a cam mechanism which serves to retract the head 117 from its barrier positioned across the lower end of chute 116, and a tension spring mechanism which serves to push the head 117a back into the chute. The cam mechanism is comprised of a double-lobe cam 118 secured upon drive shaft 54 and a cam follower roller 119 at the free end of a rocker arm 121 extending from lever 117, the latter being mounted for rocking movement about a shaft 122. The tension spring mechanism is comprised of a tension spring 123 having one end anchored at the wall of chute 116 and the other end secured to an extension rod 124 from the head end of lever 117. As the double lobe cam 118 rotates, lever 117 will thus be periodically rotated clockwise to the retracted position and tension the spring 123, and then counter-clockwise by the force built up in the tensioned spring 123.

As previously explained, the loader conveyor mechanism 55 is supported pivotally upon the same shaft 54 that is used to drive the conveyor itself. The conveyor proper is comprised of two parallel spaced endless chains 125 mounted on end sprockets 126, 127 spaced by a frame member 128. Sprockets 126 are secured upon drive shaft 54 and hence, serve to drive the endless chains 125. Spaced divider plates 129 preferably of rubber extend between the chains 125 to establish separate compartments for each full bobbin B, and a cover plate 131 is also provided for the upper flight of the chains 125. Cover plate 131 is attached to a circular support plate 132 also mounted rotatably about the axis of shaft 54, and a resilient flap 133 secured to the wall of chute 116

bridges the gap between this chute and the end of cover plate 131 so as to provide a continuous guide wall for the bobbins as they are transferred from the lower end of the chute into the receiving end of the endless conveyor chains 125.

The entire loader conveyor unit 55 is adapted to swing about the axis of shaft 54 as shown in FIG. 6 so as to assist in a proper loading of the full bobbins into box 23, and the weight of the pivotally mounted loader conveyor 55 is balanced in part by a tension spring 134 having one end adjustably anchored in a threaded connection 130 and the other end connected to one end of a link 135, the other end of link 135 being pivotally connected to plate 132 at a distance r from the axis of shaft 54. The balancing force is such that the conveyor unit 55 will assume a near horizontal position when no bobbins are present on conveyor chains 125. When the bobbin box 23 is empty and bobbins are on the chains 125, the conveyor unit 55 will swing downwardly with a slight force to a near vertical position. In this position the counter-balancing force is at a minimum because the moment arm through which the spring force is applied is at a minimum. As the conveyor unit begins to swing upwardly from its near vertical position simultaneously with delivery of bobbins from the discharge end of conveyor 125, the moment arm gradually increases and hence, so also does the balancing force increase. The first bobbins to be packed in box 23 will tend to be piled up against the front wall 23a of the box. As more and more bobbins are released from conveyor chains 125, the conveyor unit 55 will also then begin to swing upwardly so that the bobbins will thereby tend to build up in the box in a generally triangular pattern starting from the lower front corner of the box. Spring 134 thus performs one function in automatically raising the loader 55 to an upper, out-of-the-way position when no bobbins are being doffed so as to facilitate removal and replacement of the bobbin box 23, and it serves a second function in conjunction with the variable moment arm to apply through the rubber plates 129 a comparatively gentle force against the full bobbins B which causes them to be properly loaded in the box in an oriented manner so as to minimize the possibility of damage to the yarn package on the bobbin.

Donner unit

The donner unit, shown in assembly in FIGS. 1-4 and in detail in FIGS. 10-20, is comprised generally of a magazine for holding a supply of empty bobbins and an endless conveyor which functions to transfer the bobbins from the magazine to a donner head from which they are released one-by-one onto the empty spindles after the doffer unit operating in advance of the donner unit has removed the full bobbins.

The entire donner unit is mounted on a horizontal platform 136 which is held in place on the machine by a pivotal connection 137. The remaining weight of the donner unit is carried by two arcuate flat tracks 138, 139 on which rollers 141 roll, these rollers being mounted at the underside of platform 136. By supporting the entire donner unit in this manner, the donner head 142 can be easily shifted towards or away from the line of spindles by means of a reversible gear motor M4 which preferably includes a magnetic brake to prevent any override after the energizing circuit to the motor has been broken. The output shaft of motor M4 has secured to it a crank arm 143 and to the outer end of this arm is articulated one end of a connecting rod 144. The other end of rod 144 is connected to the underside of the donner platform 136 by a ball and socket joint 145. Consequently, when motor M4 runs in one direction, platform 136 will move the entire donner unit including the donner head 142 toward the line of spindles and conversely as motor M4 is reversed, the donner unit including head 142 will move away from the line of spindles. Motor M4 includes two sets of limit switch contacts SW9, SW10. The motor can

be controlled manually by in and out switches SW7, SW8, and it can be controlled automatically by a V-shaped pivotally mounted spindle feeler switch SW6 by which the donner head 142 is automatically maintained in proper alignment with each individual spindle to be donned thus assuring accurate placement of the empty bobbins on each spindle as the donner head reaches it.

Mounted on platform 136 is an endless conveyor which comprises upright end shafts 148, 149 having upper and lower sprockets 151, 152 secured thereto. Upper and lower chains 153, 154 extend between these sprockets and are provided with spaced plastic blocks 155 which establish compartments on the conveyor for receiving individual empty bobbins *b* as they feed into the conveyor from the magazine which will be described later.

The lower end of sprocket shaft 148 terminates in a coupling to the drive shaft of a torque motor M3 which is arranged to be energized continuously during the time that the doffer-donner machine is traveling along the spinning frame. This torque motor, which can be a model DCTM20-1 manufactured by Giannini Controls Corporation, exerts a continuous torque on shaft 148 tending to drive the conveyor chains 153, 154 but the latter have an intermittent movement as the bobbins are released intermittently from the donner head 142.

As shown in FIGS. 10, 11 and 16, the donner head 142 is pivotally mounted at its sides on horizontal trunnions 140 for a rocking movement which is involved in effecting transfer of an empty bobbin *b* from the donner head 142 onto the top of an empty spindle. At the underside of the donner head a cam plate 142a is provided which is adapted to be engaged by the top of the spindle 76 as the donner head approaches the spindle. This cam plate is located in the path of the spindle just aft of the donner head aligning switch SW6 so that as the cam plate slides along the top of a spindle about to be donned, the donner head 142 will be caused to rock upwardly about the trunnions 140 so as to raise the bottom of the butt of the bobbin in the donner head slightly above the top of the spindle. Further movement of the donner head along the spindle line causes the top of the spindle to leave the cam plate 142a which then allows the donner head to rock downwardly by gravity whereupon the top end of the spindle receives the butt end of the bobbin, and as movement of the donner head continues along the spindle line, the bobbin will be dragged by its butt end out of the donner head and slide down on the spindle to its final rest position.

To facilitate placement of the bobbin butt over the top end of the spindle that part 142b of the donner head which holds a bobbin ready for release may be raked, as shown in FIG. 11, away from the direction of travel of the donner head so that the bobbin about to be released is tilted slightly to better receive the top of the spindle as the cam plate 142a leaves the spindle and allows the donner head to rock downwardly. A thread guide 150 is mounted on the front of donner head 142.

As shown in FIG. 16 the donner head 142 includes an arrangement by which a group of three bobbins is always accommodated in a space between one arm 156a of a double arm rotatable driver 156 and an abutment spring 157 in the donner head. The arms 156a of the driver 156 are located 180° apart and this driver is arranged for periodic rotation in increments of 180° so as to feed the empty bobbins one-by-one from the delivery end of the conveyor chains 153, 154 to the donner head as the bobbins are released one-by-one from the donner head onto each empty spindle as the bobbins are doffed.

Driver 156 is mounted upon an upright rotatable shaft 158 and a sprocket 159 is also secured to the upper end of this shaft to drive it. Sprocket 159 is connected by a chain 161 to another sprocket 162 which is mounted at the upper end of shaft 149 for rotation about the axis of this shaft. Sprocket 162 is not secured rigidly to shaft 149 but rather is connected to it as shown in FIGS. 18, 19

5 by way of a spiral spring 163, the inner end of the spring being secured in a transverse slot 149a in the upper end of shaft 149 and the outer end of this spring being secured to an anchor pin 164a on plate 164 which forms part of a rotatable hub assembly 160 on shaft 149 that also includes sprocket 162.

In a manner which will be presently explained, shaft 149 is released periodically for rotation in increments of 180°, this shaft 149 having a torque constantly applied to it by chains 153, 154 and drive sprockets 151, 152 on shaft 148 which as previously explained is coupled to torque motor M3. Each time that shaft 149 rotates through 180° it turns spring 163 which therefore imparts a drivable torque to sprocket 162 even though the latter cannot move at this particular instant. This drive torque is, of course, transmitted by chain 161 and sprocket 159 to shaft 158. Thus, this captive torque created by winding spring 163, is able to rotate shaft 158 and bobbin driver 156 through 180° with a rather high velocity each time the latter is released, which occurs each time that an empty bobbin is released from the donner head.

Each time that shaft 158 rotates through 180° it also releases shaft 149 for rotation through 180° to again build back the torque in spring 163 which had been previously utilized in the rotation of shaft 158. The lock-up mechanism for doing this, as shown in FIG. 20, is comprised of a double lobe cam 165 secured to the bottom of shaft 149, the flat-faced lobes 165a being displaced 180° apart. A similar double lobe cam 166 is secured to the bottom of shaft 158. In association with these two cams is a triangular follower plate 167 which is the actual trigger element for this particular lock-up mechanism. Plate 167 includes roller followers 168, 169 mounted at two corner portions of the plate and which are adapted to engage the lobes of cams 165, 166. A pivotal mounting 171, cushioned in rubber to absorb shock, is located at the remaining corner portion of plate 167 so that the latter can be oscillated back and forth about the pivot axis 171. Thus, each time shaft 158 and cam 166 begin to rotate thru 180° counter clockwise upon release of a bobbin from the donner head by contact with the top of a spindle, plate 167 is rocked counter-clockwise about the pivot 171 by cam follower 169 which causes cam follower roller 168 to be released from the near cam lobe 165a, thus freeing shaft 149 for rotation under the constant torque applied from motor M3. As the lobe 166a on cam 166 reaches the final part of its 180° movement it engages the other follower roller 168 to rock plate 167 clockwise so that roller 168 will be in the proper position to be contacted by the other cam lobe 165a' thus stopping rotation of cam 165 and shaft 149 and completing one cycle of operation of the donner unit. Shortly after this lock-up has occurred, the next bobbin *b* is released from the donner head and the cycle is then 55 repeated.

Magazine

The magazine 172 which stores a supply of empty bobbins is shown in FIG. 17. In the illustrated embodiment, 60 the magazine has a quadrantal configuration and comprises seven feed channels 173 arranged in side-by-side relation, each channel holding twenty bobbins *b* or a total of a hundred and forty bobbins which would be sufficient to take care of an average size spinning frame. The magazine 172 is fitted into place adjacent the bobbin conveyor 153, 154 as shown in FIG. 12 and held in that position by a pair of pivoted, spring loaded latch levers 174, the toes 174a of which engage behind an upper flange 175 on the magazine. Another lower flange 176 on the magazine is engaged in a slot in the donner structure.

70 Bobbins are pushed downwardly in the magazine channels 173 to the discharge ends under spring pressure. This pusher mechanism is comprised of a pusher arm 177 for and in each channel 173, there accordingly be-

ing seven of these arms mounted for free pivotal movement on a horizontal shaft 178. This shaft is suitably journaled in the donner structure and is adapted to be manually rotated by an operating lever 179 coupled to one end of the shaft. The several pusher arms 177 are spaced from each other and maintained in alignment with their respective magazine channels 173 as shown in FIG. 10 by free bushings 181 on shaft 178. In addition to the free bushings 181, two spaced rocker sleeves 182, which also serve as spacers for certain of the pusher arms are splined to shaft 178 so as to rotate therewith. Rocker arms 183 integral with these sleeves are connected together at their outer ends by a lifter rod 180 extending parallel with shaft 178 and which function to engage and rotate all of the pusher arms to their upper horizontal position so that the toe portions 177a will be in the proper position over the entrance ends to the magazine channels to establish a spring-loaded contact with the bobbins in the channels. This is, of course, done by rotating the operating lever 179 through 90° from the vertical rest position shown in FIG. 10 of the drawing to a horizontal position, and a latch mechanism is provided to hold this lever in the horizontal position. This latch mechanism is comprised of a spring loaded latch pin 184 adapted to engage and be retained by a latch member 185 seen in FIG. 4. Latch pin 184 can be released from the latch member 185 by pressing inward upon a plunger rod 186 shown in FIG. 10 which slides within the hollow operating lever 179. If desired, a pivotally mounted handle 187 can be provided at the outer end of lever 179 for easier manipulation.

By lifting lever 179 slightly above the horizontal position, it will be seen from FIGS. 10 and 12 that lifter rod 180 will engage arms 188a of a pair of spaced levers 188 journaled for rotation on shaft 178. The lower ends of levers 188 are pivotally connected at 189 to the outer free ends of spring loaded latching levers 174 so that when levers 188 are actuated, latching levers 174 will release from the flange 175 on magazine 172 thus permitting an empty magazine to be removed and replaced with a full one.

The spring loading for each pusher arm 177 is constituted by a tension spring 191 operating through a spring link 192. The upper end of each spring link 192 is connected by a pivot pin 193 to its associated pusher arm 177 at a point comparatively close to the rotational axis for the arm represented by the center of shaft 178. The lower end of the spring link is secured to one end of a flat bar 190 and the opposite end of the latter is secured in a horizontally extending fitting 197 located on the inner face of an upright wall of the donner structure. One end of each tension spring 191 is anchored on this upright wall and the opposite end is secured to an intermediate part of its corresponding spring link 192.

The spring links 192 are installed for two purposes. One is to provide the proper lever arms with relation to the position of the pusher arms 177 and the second is for space consideration to allow a long enough spring 191 to go through the necessary stroke. These pusher arms and their loading springs are required because of the fact that the bobbins are being discharged from a channel section of the magazine that starts out with its upper entrance end horizontal and terminates with its lower discharge end vertical. That is to say, the bobbins in each channel go through a 90° change in attitude in moving downward through the channel. When the channel is completely full with bobbins, enough bobbin weight is obtained from the stack of bobbins to force the lower bobbins downwardly and into the conveyor. However, as each channel progressively unloads, this force from the bobbins progressively diminishes and the pusher arms must then furnish more force on the bobbins. Since it is desired that the force on the bobbins in the channels at the discharge end remain essentially the same regardless of the number

of bobbins in each channel, the force applied by the pusher arms 177 should thus vary from practically nothing when the channel is full to a maximum when the channel is almost empty. This is accomplished by allowing the contact point 193 of the arm from spring 191 to be virtually over center relative to the axis of shaft 178 as far as its spring pressure is concerned so that when the pusher arm 177 occupies a horizontal position at the top of a magazine channel full of bobbins the spring force is developed almost directly into shaft 178 and the moment arm from the pivot pin 193, which connects the upper end of spring link 192 to push arm 177, to the center of shaft 178 is virtually zero. This moment arm increases progressively as the pusher arms 177 move downwardly through a 90° arc to thus impart a progressively increasing force to compensate for the progressively decreasing force provided by the weight of the bobbins still in each channel. After all bobbins are discharged from all magazine channels 173, the operator raises the lever 179 to its upper horizontal position and lever 179 becomes latched in this position on latch member 185. In this position the pusher arms are raised above the upper ends of the magazine channels 173 so that the empty magazine can then be removed. This is accomplished as previously explained by then raising the lever 179 slightly above the horizontal detented position thus releasing the latching levers 174 from the magazine flange 175.

In normal operation, the empty bobbins *b* are removed one-by-one from the magazine and released from the donning head 142 onto the empty spindles. Should a spindle fail to doff; a safety device is installed to prevent the donner unit from trying to place an empty bobbin on this particular spindle. This safety device as shown in FIG. 2 is comprised of a roller follower 195 mounted on a hinged, spring loaded plate 196 so that roller 195 lies approximately in line with the toe 85a of bobbin lifting arm 85, and it performs two functions. First, it is generally in line with the butt end of a bobbin which is to be doffed and so will contact the butt end if, for some reason the lifter arm 85 does not remove it from the spindle. It is, of course, so positioned that it will clear the spindle itself. In this manner, it becomes a safety to keep the donning mechanism from trying to install an empty bobbin on a spindle from which the full bobbin has not been removed. Switch SW4 which is actuated by movement of this roller follower 195 and plate 196 functions to break the entire electrical circuit of the machine as shown in FIG. 21 causing it to stop on the track before the donner head 142 reaches the undoffed spindle. The second function is to contact the head or foot end of the spinning frame and stop the entire machine automatically after the last spindle has been donned.

Operation

In the wheel-around position of the doffer-donner machine, which is the position adopted when the machine is either not in use, or is being wheeled from one spinning frame to another, the support plate 17 which carries the entire operating mechanisms of the donner and doffer components is preferably at its lowermost level on the truck base 10. This keeps the center of gravity of the machine low and hence, stabilizes it against accidental tipping over and also the machine is then in its strongest structural position.

When a spinning frame is ready to be doffed, the ring rail is lowered and the frame is shut down. The doffer-donner machine is then brought close alongside the frame at one end thereof. The compressed air line is then connected up to nipple 32 and valve handle 29 is then shifted to the position such that compressed air will be admitted to the upper ends of the cylinders 24. This causes the cylinders 24 and hence, plate 17 and all the doffer-donner mechanisms supported thereby to be raised on truck base 10 until the supporting sheaves 41, 46 are slightly higher

than the support rail 47. With the grooves in these sheaves now in line with rail 47, valve handle is shifted to its other position which permits plate 17 to lower until the sheaves rest upon the rail. The third point of support for the machine is then the contact between the lower guide wheel 40 and the lower guide rail 60. After the weight of the machine has been transferred from the truck base 10 to rail 47, continued movement of the piston rods 26 upwardly in their cylinders 24 will cause the truck base 10 to be raised clear of the floor. Also, such movement will then cause detent 42 to reach and rock lever 71 to actuate rod 69 and cam plate 65 which permits arms 58, 63 carrying brush block assembly 57 and switch SW5 to move these two elements into their operative position, the brush block assembly then engaging bus bar 56 to pick up the necessary power supply for operation of the doffer-donner, and the switch SW5 being positioned for periodic closing of its contacts as the switch button periodically engages the series of spaced bosses 74 along rail 47.

Crank handle 99 then is rotated to release lever 88 so that the hood 86 also moves from its retracted position into the receiving position over the bobbins. The bobbin lifter arm 85 is also caused to be similarly shifted to its forward, operative position as lever 88 is released.

With reference to the circuit diagram of FIG. 21 switch SW1 is then actuated to the "on" position. This action applies power to the bobbin conveyor on the donner motor M3 and also to motor M4 which is the donner aligning motor and which is positioned in two different manners. First, the operator has manual control of both the inward and outward position of the entire donner. Second, the donner mechanism can be controlled automatically through switch SW6 by physical contact with the top ends of the spindles after installation on the rail has been accomplished. The operator then closes switch SW7 which is a normally open switch which parallels the automatic switch SW6 so that the donner mechanism moves forward into operative position toward the spinning frame. During the cycle when the donner is moved back into its own machinery and away from the spinning frame the donning head 142 on the front of the donner is moved up out of contact position with the spindles, and it is latched in this position by latch 194. After the operator has held switch SW7 closed for an appropriate length of time, the donning mechanism moves all the way to its front position over the top of the spindles, the contacts of limit switch SW9 open to stop motor M4 which was motoring the donner to the front position and the donning head 142 is unlatched as latch member 194 strikes the latch release 194a and drops into operating position in line with the row of spindles 76. With the donner in the operating position, as soon as the frame is drawn down for doffing, pushbutton switch SW3 which is located on the doffer-donner machine is momentarily pressed and this switch energizes the coil of switch SW2 to close its contacts. This closed switch in turn furnishes power not only to a holding circuit which holds its own coil in energized position through the normally closed contacts of safety switch SW4 but it also furnishes power to motor M2 which is the drive motor for the transfer belt, and to motor M1 which is the tractor motor, and to the doffer solenoid 62 which is periodically energized as switch SW5 is periodically actuated by the spaced bosses 74 on rail 47.

After switch SW3 has been pressed momentarily to thus in general furnish power to the doffer-donner machine, the latter is then under its own power to run to the opposite end of the spinning frame. The full bobbins B are doffed in succession by periodic upward movement of lifter arm 85, each bobbin being driven upward to enter hood 86 and be carried by transfer belt 107 to and into transition chute 116 where the bobbin drops to a level for discharge onto the receiving end of loader con-

veyor 55. Bobbins are then discharged from this loader into the bobbin box 23 filling the same in an orderly manner with all bobbins side-by-side and oriented in the same direction, as shown in FIG. 6.

As each full bobbin B is doffed leaving an empty spindle 76, that spindle will be approached by the aligning switch SW6. If the donner head 142 is in the correct position of alignment with this particular spindle, switch SW6 will not be actuated and the under surface of cam plate 142a will next ride into contact with the upper end of the spindle. This causes the donner hood 142 to rock upwardly to the point where the bottom of the butt of the empty bobbin b in the donner head is high enough to receive the upper end of the spindle as the latter leaves cam plate 142a. With the upper end of the spindle now in the butt of the empty bobbin, continued movement of the machine along the spinning frame will drag that bobbin out of the donner head 142 and the bobbin will then continue to drop on the spindle until seated in the proper position.

Should the top of any particular spindle to be donned not be in proper alignment with the donner head, switch SW6 will be actuated in one direction or the other, as the occasion requires, to cause the donner aligning motor M4 to shift the whole donner unit including the donner head 142 either in or out until a proper alignment has been reached.

As has been explained, a safety mechanism is operative to prevent the donner unit from trying to don an empty bobbin on a spindle which has failed to doff. If, for some reason a full bobbin B has failed to doff and is still on the spindle as cam follower roller 195 reaches this particular undoffed bobbin, roller 195 will strike against the butt of this bobbin and cause the contacts of switch SW4 to be opened. This, of course, interrupts the holding circuit for the coil of switch SW2 as shown in FIG. 21 and hence, interrupts the power supply to the tractor motor M1 thus stopping the doffer-donner machine before the donner head 142 reaches the undoffed spindle.

After all spindles have been doffed and the machine is thus now approaching the end of the frame, cam roller 97 contacts a cam, not shown, which is secured to the lower guide rail 60 causing lever 95 to be rocked and pull downwardly on cable 93 which causes lever 88 to be actuated to shift hood 86 back to its retracted position and to also shift the bobbin lifter arm 85 to its retracted position thus removing all of the elements out of the way to protect them against damage which would otherwise be caused by any obstruction in the path of movement at the end of the frame, and also prevent possible damage while the unit is being moved about.

Also, as the doffer-donner machine nears the end of the frame, and after hood 86 and bobbin lift-off arm 85 have been retracted, safety switch SW4 is actuated by a stop member, not illustrated, suitably positioned in the path of roller 195. As the contacts of switch SW4 open, the power to the tractor motor M1 is interrupted and hence, the doffer-donner machine is brought to a quick stop. However, at this time, the electrical components of the donner unit are still under power. The operator then actuates switch SW8 which retracts the donner unit to the proper position for transport. This operation also elevates the donning head 142 into a position away from the spindles and latches it in this position. After the contacts of limit switch SW10 have been opened which means that motor M4 has now stopped and the donner unit has been completely retracted, the operator has only the further jobs of disengaging the machine from the track rail 47 and turning off switch SW1 which cuts off power from the entire machine. To disengage the machine from rail 47, a compressed air hose is then connected to nipple 32 and control valve 28 is actuated into the position to cause the machine to be lifted off and clear the sheaves 41, 46 from track rail 47 after which the machine can be lowered back to its lowermost position

on the truck base and rolled out into the room. The machine is then ready to be rolled to the next frame to be doffed.

A somewhat modified construction is shown in FIGS. 23-25 for the transfer mechanism by which full bobbins B, when propelled upward off their seats on the spindles by means of the periodically actuated lifter arm 85, are delivered to the loader conveyor 55 from which they are deposited in the bobbin box. The modified transfer mechanism as shown in these views is comprised of a receiving hood 200 which includes a pivotal connection 201 at its upper end to permit the hood to be shifted between a forward operating position as shown in the drawings and a retracted position substantially flush with the front edges of the upwardly extending parallel spaced side plates between which the hood is supported. These side plates are similar to the side plates 87 of the previously described embodiment and hence, have been given a similar number 87'. A lever 88' similar in function to lever 88 of the previous embodiment, is connected to hood 200 so as to shift it between its forward and retracted positions in generally the same manner as provided for the previous embodiment.

Located at the bobbin entrance into the lower end of hood 200 is a door structure which comprises a pair of doors 202 preferably made from nylon and inclined upwardly. The doors are hinged along their outer side edges by means of hinge pins 203 for opening inwardly when struck by the upper end of the bobbin B. These doors are biased to a closed position by torsion springs 204 surrounding the hinge pins and close automatically as soon as the butt of a bobbin has passed through them. As the doors close immediately behind the bobbin, they form an inclined ramp for the butt of the bobbin to slide downwardly onto an endless rubber belt structure 205 mounted on spaced pulleys 206, 207, the shaft 208 for pulley 207 being extended laterally and having secured thereto a driven pulley 209 which is connected by belt 210 to a drive pulley 211 on the shaft of motor M2. The traveling belt structure 205 carries the bobbin through an exit door 212 of flexible material, this door being mounted pivotally at 213 and biased by a tension spring 214 connected to its upper end so that the lower edge of the door bears against the belt structure 205 at the end pulley 206.

After the bobbin has passed through the exit door 212 it is deposited upon the upper end surface 215a of a combined escapement and bobbin aligning device 215 which is inclined and pivotally mounted at 216 to a support 217. Movement of the escapement device 215 between the position shown in the drawing, wherein the surface 215a serves to momentarily stop, align and hold a bobbin as it comes off the belt structure 205, and a retracted position which permits the bobbin to drop through the transfer chute 218, is controlled by a solenoid 219 mounted on the support 217. The armature 220 of this solenoid is connected by a link 221 to the aligning device 215 such that when solenoid 219 is energized, its armature 220 will pull in to the position shown in the drawing and thus move the end surface 215a to the bobbin intercepting and holding position. When solenoid 219 is de-energized, the armature 220 will drop out and cause the end surface 215a to shift to its retracted position and allow the bobbin to pass downwardly through transfer chute 218. This drop out and retraction movement takes place by gravity forces due to the way in which the components are inclined, and also by the forces stored in spaced biasing springs 222 which are secured to the pivotally mounted escapement device 215.

Solenoid 219 arranged to be energized periodically in the same manner as the solenoid 62 which operates the bobbin lift-off mechanism, i.e. by the bosses 74 on rail 47 which periodically actuate a switch SW11. Closure of the contacts of this switch is thus synchronized with ejection of a bobbin off its spindle and hence, as-

sures that the end surface 215a will always be in the proper position to receive, align and stop a bobbin as it comes through the exit door 212.

As each doffed bobbin B reaches the bottom of transfer chute 218, its motion is arrested by the upper broad surface 223a of a kick-down lever mechanism 223 which is connected by parallel spaced rocker arms 224 on a horizontal rock shaft 225. Another rocker arm 226 on this rock shaft is connected to one end of a tension spring 227, and the opposite end of this spring is connected to the armature 228 of another solenoid 229 which is arranged to be periodically energized by closure of the contacts of another switch SW12, these switch contacts being actuated periodically by means of a cam sleeve 230 on shaft 54 which drives the loader conveyor 55 so that each full bobbin can be dropped out of transfer chute 218 at the proper time to fall into one of the compartments established between adjacent blades 129 on the conveyor chains 125. Solenoid 229 is illustrated in its energized position, the kick-down lever 223 being accordingly shown in its down, or intercepting position which arrests movement of the bobbin B downwardly through chute 218. When solenoid 229 is de-energized, a torsion type biasing spring 231 surrounding rock shaft 225 and coupled to one of the rocker arms 224 serves to rotate the kickdown lever 223 clockwise to the bobbin-release position indicated in broken lines.

For assisting in the transfer of bobbins from the lower end of chute 218 into the compartments of the loader conveyor 55, an oscillatory plunger mechanism is utilized. This plunger mechanism comprises two parallel spaced oscillatory arms 232 each extending outward from a hub 233 which is mounted freely on shaft 54. A plunger head surface 234 adapted to engage and receive the bobbin as it leaves chute 218 extends between the outer ends of arms 232. Each arm 232 is biased to a lower rest position by means of a tension spring 235 and is periodically rotated counter-clockwise as viewed in FIG. 24 and then released to drop back to the rest position by means of a pin and pawl arrangement. As seen in FIGS. 23 and 24, a disc 236 for each pin and pawl drive is mounted upon drive shaft 54 for the loader conveyor so as to rotate with this shaft. Each disc 236 is provided with four equally spaced pins 237 which project laterally from one face of the disc. These pins are adapted to cooperate with the toe 238a at one end of a pawl 238 which is pivotally mounted intermediate its ends upon the arm 232, and includes a torsion type loading spring 239 which functions to maintain the pawl toe 238a engaged with one of the pins 237 until released by a clockwise rocking of the pawl as the opposite end 238b of the pawl strikes against an abutment 241. As the loader conveyor drive shaft 54 rotates, so also will the pins 237 rotate and hence, effect periodic engagement with the pawl toe 238a thus causing the arm 232 to be picked up and rotated clockwise from the position of rest shown in the drawing until the pawl is released. Since the pins 237 rotate with drive shaft 54, then it follows that oscillatory motion of the arms 232 and the plunger surface 234 will be properly synchronized as to assure proper transfer of the bobbins in succession to successive compartments on the load conveyor.

In order to make certain that each bobbin stays in its compartment on the loader conveyor just subsequent to transfer into the compartment by the plunger head, a hold-down arrangement can be utilized. As illustrated, this hold-down includes a rocker plate 242 engageable with the bobbin and extending from a horizontal rocker shaft 243, a rocker arm 244 on rocker shaft 243 and a connecting link 245, one end of this link being articulated to rocker arm 244 and the other end being fastened to one of the oscillatory arms 232 through a pin-and-slot connection 246. A biasing spring 247 is connected to rocker arm 244 and oscillatory movement of the rocker

plate 242 is thus synchronized with oscillatory movement of plunger head 234 on the oscillatory arms 232.

The various components of the modified transfer mechanism operate in the following manner. As each full bobbin B is doffed from its spindle, passes into the hood 200 and is then passed butt first to belt 205, solenoid 219 will be energized so that surface 215a of the escapement is actuated to the intercepting position shown in full lines to thus catch and arrest and align the bobbin as it leaves the belt and passes through door 212 into the upper end of the transfer chute. Solenoid 219 is then de-energized causing the escapement surface to move away from its blocking position whereupon the bobbin will then roll down the inclined side wall of chute 218 and come to rest momentarily upon the surface 223a of kick-down lever 223, thus momentarily blocking release of the bobbin from the lower, discharge end of the chute, and thereby preventing the bobbin from dropping partway into the path of and jamming movement of the plunger head which, in the meantime, has been picked up by the pawl mechanism 237-238. When plunger head 234 nears the end of its advance clockwise stroke, solenoid 229 is then energized causing the kick-down lever 223 to retract to the broken line position thus permitting the bobbin that had been stopped by the lever surface 223a to drop out of the chute onto the surface of the advancing plunger head. Since operation of the plunger head is synchronized with movement of the loader conveyor, the bobbins will therefore be deposited properly in succession from the plunger head into successive compartments on the conveyor, and held down momentarily at the time of their deposit, by downward pivotal movement of the rocker plate 242 as the latter is actuated through link rod 245 when the plunger head is released by the pawl for return movement to its lower, receiving position. This completes one cycle of operation which is then repeated for each bobbin as it is received in the upper end of the transfer chute.

A somewhat modified construction for the donner is shown in FIGS. 26-28. As has been explained, and as shown in FIG. 16, a group of three empty bobbins is held in the donner head 142 with a rather high spring load due to the torsional force applied by the driver arm 156a. In certain cases this spring loading may cause the bobbins to move in the donner head so fast that the middle one of the three bobbins in taking the place of the bobbin which has just been picked off by a spindle, will also impart an ejecting force to the latter which may prevent the picked-off bobbin from settling downward in the proper manner on its spindle and even in some cases to fly completely off the spindle. To prevent this possibility, the modified construction illustrated in FIGS. 26-28 can be employed. This includes a stationary guide 248 positioned at the discharge side of the donner head 142 by means of a bracket 249 which is secured to one wall of the overall donner support structure. While the guide 248 is stationary with respect to the donner structure, it nevertheless moves with the latter and hence, always maintains its position of alignment with the discharge side of the donner head as the latter is continuously centered with respect to the spindle line by the feeler switch operated donner aligning mechanism. Guide 248 includes a pair of curved side walls 248a, 248b which, as shown in FIG. 28, converge in the direction counter to the direction of movement of the doffer-donner along the spinning frame, and a top sloping wall 248c. As each empty bobbin is dragged from the donner head upon being picked off by a spindle from which a full bobbin has just been doffed, the upper portion of the bobbin will enter the guide 248 and thus be held vertically and eliminate any tendency of the bobbin to chatter as it drops on the spindle, being aided perhaps by the sloping top wall 248b.

On many types of textile machines such as spinning frames and the like provided with a row of spindles to

be doffed, the individual spindles are each provided with a weight-loaded latch connected to the spindle rail and which normally rests just above the bottom flange for the tape driven pulley on the spindle. This latch keeps the spindle from being moved upwardly in its bearing as an upward force is applied to the bobbin while doffing manually. These latches may become loose or even broken and hence rendered inoperative and thus may permit of so much vertical play of the spindle in its bearing as to interfere with proper operation of the doffer unit of this invention which, as has been previously explained, has a limited stroke and relies upon application of an impact type force to the bobbin to unseat it from the spindle and drive it upwardly into the receiving hood 86.

FIGS. 29-31 illustrate an arrangement providing a temporary hold-down for each spindle as the doffer unit reaches it. The hold-down thus eliminates the necessity for doing a repair job on the individual latches for the spindles on each textile machine before the doffer-donner machine can be installed. As shown in these three figures of the drawing, the hold-down includes a flat plate 251 having an essentially dog-leg configuration, the plate being pivotally mounted at one end thereof on a vertical pivot pin 252 which is secured to a bracket structure 253 mounted on the front face of the upright supporting plate 17 of the machine, the hold-down plate 251 being movable in a horizontal plane in the space between the upper and lower flights of sprocket chain 43. A torsional loading spring 254 which surrounds the pivot shaft functions to urge plate 251 outwardly from the main support plate 17 towards the tape driven pulley 255 on the lower part of spindle 76, it being noted from FIGS. 30 and 31 in particular that the lower face of a middle part 251a of plate 251 engages the upper face of the lower flange 255a of the tape driven pulley and thus prevents the pulley and hence, the remainder of the spindle structure from moving in an upward direction.

The outer toe portion 251b of plate 251 is arranged for guiding movement in a horizontally slotted part 256a of a guide block 256 which is secured to the far side of the opening in plate 17 provided for operation of the bobbin lifter arm 85. A pin 257 which passes through the toe portion 251b serves as a stop against the side of block 256 to prevent the plate 251 from moving completely out of the guide block by action of spring 254. The combination of plate 251 operating in the guide slot of block 256 permits pivotal movement of the plate but restrains it against movement either upward or downward and also prevents it from twisting upwardly, to some extent, while it is restraining the spindle pulley 255 against upward movement during the doffing.

It will be noted from FIG. 31 that the edge portions 251c, 251d of plate 251 to each side respectively of the center part 251a slope in opposite directions. The sloped part 251d enables plate 251 to be cammed slightly backward toward plate 17 when the plate comes into contact with each spindle. These sloped edge portions 251c, 251d also enable plate 251 to be cammed back to a greater extent when the plate engages either the head or foot end casting on the textile machine. Thus, this hold-down device becomes completely automatic in operation and is able to clear the head and foot ends of the textile machine.

In the embodiment of the invention which has been described, some manual operations are required in preparing the doffer-donner for operation after it has been placed on its supporting rails at the head end of the textile machine, particularly in clearing the castings at the head end of the machine. It will be remembered that the donning head on the donner and the guide hood and bobbin lifter arm on the doffer project over the line of spindles which is set in somewhat from the castings at the head end as well as the foot end of the machine. In the embodiment which has been described, the donning head is motored into operating position by a manually

operated control switch at the head or starting end of the textile machine and is similarly motored out of that position by a manually controlled switch at the foot end of the textile machine. The guide hood and bobbin lifter arm on the other hand are manually released from their retracted positions at the head end of the frame and are automatically retracted again at the opposite end of the textile machine to clear the foot end casting.

In order to make the machine more automatic with respect to operation of the donning head, guide hood and bobbin lifter arm at the head end as well as at the foot end of the textile machine in order to clear the castings at those ends, certain minor modifications can be made to the doffer-donner machine previously described, and these modifications are illustrated in FIGS. 32-35. With reference now to these views, it will be seen that the wiring diagram of FIG. 35 is similar to the wiring diagram of FIG. 21 except that the latter shows a single phase system whereas, the former is now a 3-phase system. The motors and switches and other components which appear on FIG. 35 and which have the same function as the corresponding components in FIG. 21 have been given the same reference numerals but with primes added thereto for purposes of distinguishing between the two embodiments. In addition to the ten switches SW1 to SW10 which appear in FIG. 21, the 3-phase system of FIG. 35 includes four other switches SW11, SW12, SW13 and SW14. All of these switches are carried by the doffer-donner machine and are shown in FIG. 32. Switch SW11 is carried at the upper end of support plate 17' and its depending actuating member 260 is adapted to strike against an abutment 261 located on the textile machine near the foot end thereof as shown in FIG. 34 so as to actuate the contacts of this switch as soon as the last bobbin B' has been doffered.

Switch SW12 is mounted on the lower part of plate 17' and includes an actuating arm 262 terminating in a cam follower roller 263 which is adapted to roll on a cam track 264 mounted on guide rail 60. It will be noted from FIG. 34 that cam follower roller 97' is also arranged to ride on cam track 264 and that roller 263 is positioned in advance of roller 97' with respect to the direction of travel of the doffer-donner machine.

Switches SW13 and SW14 are also mounted one above the other on plate 17' and include roller type actuators 265, 266 adapted to strike against stationary cams 267, 268 respectively, mounted below the spindle rail near the head and foot ends respectively of the textile machine as shown in FIG. 34.

Drive motor M1' and doffer motor M2' are of the 3-phase 220 v. type and motors M3' and M4' are of the 1-phase type and are supplied with 110 v. power through transformers T1 and T2.

In the previous embodiment 1-phase power was brought to the machine by bus bar 56 and brush block assembly 57. In the 3-phase system of the modified embodiment, a similar 3-phase bus bar arrangement could be used, or an alternative arrangement would be a re-wind reel on the machine so that a 3-conductor cable trails the machine and lies on the floor as it moves along the textile machine. The plug-in point for the 3-conductor cable to the 3-phase power supply would then be preferably located at the middle of the textile machine so that a re-wind cable only slightly longer than half the length of the textile machine would be necessary.

In the previously described embodiment, arm 88 for actuating guide hood 86 was controlled by cable 93 and a latching device comprising a latching lever 91, and latch pin 92 was utilized to latch the guide hood in its retracted position. This latch was manually released by crank 99 coupled to the latching lever 91 after the guide hood had cleared the head end of the textile machine.

In the modified construction as shown in FIG. 32, provision is made for automatically moving the guide hood into operating position over the line of spindles as soon

as the guide hood clears the head end of the textile machine and the latching mechanism is arranged in a slightly different manner.

With reference to FIGS. 32-33 it will be seen that cable 93' includes a tension spring 269 inserted in the lower part above pulley 94', and the upper part of the cable is passed around another pulley 270 mounted on side plate 87' and is secured to the outer end of lever arm 88b'. Another tension spring 271 extends downwardly from arm 88b' to an anchor pin 272.

Latch lever 273 is pivotally connected at one end to lever arm 88a' and extends in a generally horizontal direction away from the textile machine. The rear end of lever 273 terminates in a detent 273a which is adapted to receive a detent pin 274 extending laterally from the vertical side plate of the pivotally mounted donner unit. Detent pin 274 thus shifts forward and backward with the donner unit and is depicted in FIG. 33 in its forward position. A compression spring 275 extends between lever arm 88a' and lever 273 to bias the latter into the upper position necessary to engage detent pin 274.

A roller 276 carried at the end of a pivotally mounted arm 277 lies above latching lever 273, and arm 277 is articulated to the upper end of a strap 278 which extends downward, the lower end of the strap being articulated to the armature 279a of the solenoid 279 mounted on the inner face of plate 17'.

Operation of the modified embodiment is as follows:

The doffer-donner machine is mounted on its rails 47, 60 in the same manner as the previously described embodiment just beyond the head end Fa of the textile machine F. In this position, cam follower roller 263 is located at the raised horizontal part of cam plate 264 as shown in FIG. 34 and hence, the contacts of switch SW12 are closed. Switch SW1' is now closed by hand. The contacts of switch SW2' are now closed since the closed contacts of switch SW12 establish a shunt around the manual start switch SW3'. Drive motor M1' is thus energized and the doffer-donner machine starts to move along rails 47, 60.

As the guide hood 86' reaches a point adjacent the head end of the textile machine, cam follower 97' will be raised to the high part of cam plate 264 and cam follower 263 will at such time still be on this high part. Upward movement of follower 97' rocks arm 95' clockwise as viewed in FIG. 32 thus tensioning spring 269 which, in turn, tensions cable 93' over-riding the counter-tension in spring 271 and applying a clockwise torque to lever 88' as viewed in FIG. 33. Hood 86' which at that time had been resting against the head end Fa of the textile machine and which is actuated by lever 88' is thus caused to shift forward into its operating position as soon as the hood clears the head end.

Cam plate 264 extends along the textile machine to such an extent that cam follower 97' retains its high position until the donner head has cleared the head end structure Fa. At this point, the preceding cam follower 263 controlling switch SW12 will have left the high part of the cam permitting the contacts of switch SW12 to open. As soon as switch SW12 opens, the energizing circuit to solenoid operated switch SW2' is broken thus opening the circuit to drive motor M1' and thus stopping the doffer-donner machine. At the same time, the contacts of switch SW13 will close as its actuator 265 strikes cam 267 and this completes a bridge across the open contacts of switch SW7' to energize the donner drive motor M4' to run in such direction as to motor the donner head structure 142 into its operating position over the spindle line. When this position is reached, limit switch SW9' is actuated to interrupt the circuit to motor M4'. Operation of switch SW9' also completes a second shunt around switch SW3' which effects reenergization of switch SW2' thereby to again deliver power to drive motor M1' and the doffer-donner machine re-starts along the spindle line doffing and donning the spindles.

After the doffer-donner machine leaves the head end *Fa* of the textile machine, cam follower *97'* rides down the slope of cam plate *264* but the guide hood *86'* and the doffer lifting arm *85* are maintained in their operating positions due to the fact that detent pin *274* has by that time moved forward with the donner structure so as to engage the detent *273a* on latch lever *273* thus holding the latter and hood *86'* against any backward movement. Switch *SW13* is also opened thus switching over from the starting circuit through switch *SW9* to a hold-in circuit through switches *SW4'* and *SW14'*.

After the last spindle near the foot end *Fb* of the textile machine has been doffed, the actuator *260* for switch *SW11* will strike its cam *261* thus closing the switch contacts and energizing solenoid *279* which causes strap *278* to pull down and bring roller *276* against latch lever *273* which in turn causes lever *273* to rotate about its pivot and release the detent *273a* from pin *274*. Due to the tension in spring *271*, the latter is now free to pull down on lever arm *88b'* causing lever *88'* to rock clockwise as viewed in FIG. 33 and shift guide hood *86'* and doffer lifter arm *85* to their retracted positions necessary to clear the foot end structure *Fb* of the textile machine.

Also, after the last spindle has been donned, switch *SW14* is operated as its actuator *266* strikes cam *268* which breaks the hold-in circuit for switch *SW2'* causing the doffer-donner machine to stop, and also provides a shunt around switch *SW8'* which energizes the donner motor *M4'* to run in such direction as to motor the donner structure rearwardly until the donner head *142* is also clear of the foot end structure of the textile machine. As the donner structure reaches its full retracted position, limit switch *SW10'* opens so that all of the electrical components of the doffer-donner machine are then in a de-energized state and the machine sits on the end of the rail until removed by an operator.

In conclusion, it will be understood that while certain embodiments of the improved doffer-donner machine have been disclosed, various changes may be made in the construction and arrangement of its components without, however, departing from the spirit and scope of the invention as defined in the appended claims.

We claim:

1. In a doffer-donner machine adapted to move longitudinally along a textile processing machine of the type having a row of upright spindles and wherein full bobbins are doffed in succession from the spindles and empty bobbins are thereafter donned in succession on the spindles, the combination comprising a doffer-donner support structure, means for mounting said support structure on said textile machine, means for driving said support structure longitudinally along the row of spindles, a doffer unit carried by said support structure, said doffer unit including doffing means engageable successively with the full bobbins for driving them upwardly from their seats on the spindles in a successive manner and a guide hood located above said doffing means for receiving and guiding each bobbin as it is driven upwardly, said guide hood and said doffing means being movable between a retracted position sufficient to clear the head and foot ends of the textile machine and a forward operating position at the row of spindles, a donner unit carried by said support structure and trailing said doffer unit, said donner unit including a magazine for empty bobbins and a donner head receiving empty bobbins from said magazine and operative to place an empty bobbin on each spindle after the full bobbin has been doffed therefrom, said donner head being movable between a retracted position sufficient to clear the head and foot ends of the textile machine and a forward operating position over the row of spindles, means operative upon movement of said support structure from the head end of said textile machine for shifting said doffing means, said guide hood and said donner head from their retracted to their forward operating positions,

and means operative at said foot end of said textile machine for shifting said doffing means, said guide hood and said donner head back to their retracted positions.

2. In a doffer-donner machine adapted to move longitudinally along a textile processing machine of the type having a row of upright spindles and wherein full bobbins are doffed in succession from the spindles and empty bobbins are thereafter donned in succession on the spindles, the combination comprising a wheeled truck base, a doffer-donner support structure upstanding on said truck base, means for mounting said support structure on said textile machine for movement longitudinally along the row of spindles, doffer and donner units carried by said support structure, periodically actuatable switch means for electrically actuating said doffer unit at each spindle and a brush block assembly for electrifying the machine, said switch means and brush block assembly being mounted on said doffer-donner support structure for movement towards and away from the spindle row of said textile machine.

3. A doffer-donner machine as defined in claim 2 wherein said switch means and brush block assembly are pivotally mounted on said doffer-donner support structure, and wherein movement thereof towards and away from the spindle row of the textile machine is controlled by a movable cam plate in cooperation with cam follower means coordinated to the pivot mounting for the switch means and brush block assembly.

4. A doffer-donner machine as defined in claim 3 wherein said doffer-donner support structure is movable in a vertical direction relative to said truck base and which further includes means actuating said cam plate upon relative movement between said doffer-donner support structure and said truck base.

5. In a doffer-donner machine adapted to move longitudinally along a textile processing machine of the type having a row of upright spindles and wherein full bobbins are doffed in succession from the spindles and empty bobbins are thereafter donned in succession on the spindles, the combination comprising a doffer-donner support structure, means for mounting said support structure on said textile machine, an electric motor for driving said support structure longitudinally along the row of spindles, doffer and donner units carried by said support structure, a safety switch located intermediate said doffer and donner units for deenergizing said drive motor, and actuating means for said safety switch located in the path of any bobbin which has failed to doff from a spindle thereby to bring said machine to a halt and prevent said donner unit from attempting to don an empty bobbin on that particular spindle.

6. Apparatus for doffing full bobbins in succession from a row of upright spindles on a textile processing machine comprising a supporting structure mountable on said textile machine for movement longitudinally along the row of spindles, a doffer unit mounted on said support structure, said doffer unit including doffing means engageable with the full bobbins for driving them upwardly from their seats on the spindles in a successive manner as said doffing means comes adjacent each spindle, a hood located above the row of spindles for receiving each bobbin as it is doffed, a transfer chute for receiving the bobbins from said hood and transferring them to a lower level, a loader conveyor of the endless type, said conveyor being pivotally mounted at one end thereof on said support structure, means for transferring bobbins from the lower discharge end of said transfer chute onto said loader conveyor at the pivotally mounted end thereof, and a bobbin box into which said loader conveyor extends for receiving the bobbins as they are discharged from said loader conveyor in an oriented manner.

7. Doffing apparatus as defined in claim 6 and which further includes means for counterbalancing said pivotally mounted loader conveyor.

8. Doffing apparatus as defined in claim 6 and which further includes means for counterbalancing said pivotally mounted loader conveyor, said counterbalancing means having a progressive characteristic variable with the angular position of the conveyor such that the counterbalancing force increases progressively as the conveyor moves in an upward direction away from the bobbins in the bobbin box.

9. Apparatus for doffing full bobbins in succession from a row of upright spindles on a textile processing machine comprising a support structure mountable on said textile machine for movement longitudinally along the row of spindles, a doffer unit mounted on said support structure, said doffer unit including means engageable with the full bobbins for driving them upwardly from their seats on the spindles in a successive manner, a guide hood located above the row of spindles for receiving each bobbin as it is doffed, a transfer chute for receiving the bobbins from said hood and transferring them to a lower level, a loader conveyor of the endless type having transversely extending compartments each of which is adapted to receive the bobbin, means pivotally mounting said loader conveyor near one end thereof on said support structure, and means actuated in synchronism with the movement of said loader conveyor for transferring bobbins from the lower discharge end of said chute into the compartments on said conveyor.

10. Apparatus for doffing full bobbins as defined in claim 9 wherein said means for transferring bobbins from the lower end of said transfer chute into the compartments on said conveyor are constituted by a pivotally mounted plunger, cam means rotatable with said loader conveyor and cam follower means connected to said plunger.

11. Apparatus for doffing full bobbins as defined in claim 10 wherein said pivotally mounted plunger is movable from a position blocking discharge of a bobbin from the lower end of said transfer chute to a non-blocking position immediately preceding and correlated with transfer of the bobbin into a compartment on said loader conveyor.

12. Apparatus for doffing full bobbins as defined in claim 9 and which further includes an endless belt located intermediate the bobbin exit from said guide hood and the upper entrance end to said transfer chute for transferring bobbins from said guide hood to said transfer chute.

13. Apparatus for doffing full bobbins in succession from a row of upright spindles on a textile processing machine comprising a support structure mountable on said textile machine for movement longitudinally along the row of spindles, a doffer unit mounted on said support structure, said doffer unit including means engageable with the full bobbins for driving them upwardly from their seats on the spindles in a successive manner, and a guide hood located above the row of spindles for receiving and directing the movement of each bobbin as it is doffed, said guide hood including inclined door means arranged at the bobbin entrance end to said hood, said door means being normally closed and openable only to allow a bobbin to enter said hood, said door means then closing to form an inclined surface along which the butt of the bobbin slides toward the exit end of said hood.

14. Apparatus for doffing full bobbins in succession from a row of upright spindles on a textile processing machine comprising a support structure mountable on said textile machine for movement longitudinally along the row of spindles, a doffer unit mounted on said support structure, said doffer unit including doffing means engageable with the full bobbins for driving them upwardly from their seats on the spindles in a successive manner, a guide hood located above the line of spindles for receiving each bobbin as it is doffed, a transfer chute for receiving the bobbins from said hood and transferring them

to a lower level, means actuated periodically in timed relation to the operation of said doffing means for blocking the upper entrance end to said transfer chute to stop and align each bobbin as it comes from said guide hood and then unblocking said entrance end to permit the bobbin to be transferred through the chute to the lower discharge end therefrom, a loader conveyor of the endless type having transversely extending compartments each of which is adapted to receive a bobbin, means pivotally mounting said loader conveyor at one end thereof on said support structure, and means actuated periodically in synchronism with the movement of said loader conveyor for releasing said bobbins from the discharge end of said transfer chute and for transferring them into the compartments on said conveyor.

15. Apparatus for doffing full bobbins as defined in claim 14 wherein said means for periodically blocking and then unblocking the upper entrance end to said transfer chute is constituted by an escapement device including a wall portion movable into and out of blocking position with respect to the entrance end to said transfer chute, and a solenoid for actuating said escapement device, energization of said solenoid being controlled by periodically actuated switch means correlated to operation of said doffing means.

16. Apparatus for doffing full bobbins as defined in claim 14 wherein said means for releasing bobbins from the discharge end of said transfer chute includes a kickdown device having a wall portion movable into and out of blocking position with respect to the discharge end of said transfer chute, and means for periodically actuating said kickdown device in accordance with movement of said loader conveyor.

17. Apparatus for donning empty bobbins in succession onto a row of upright spindles on a textile processing machine comprising a support structure mountable on said textile machine for movement longitudinally along the row of spindles, a donner unit including a head from which empty bobbins are donned onto the spindles, means mounting at least said donner head on said support structure for movement thereof towards and away from said row of spindles, and reversible drive means responsive to any misalignment between said donner head and a spindle to be donned for actuating said donner head in such direction as to restore the alignment.

18. Apparatus for donning empty bobbins as defined in claim 17 wherein said reversible drive means includes a reversible motor and which includes a feeler switch carried by said donner head and located in the line of travel of said head along the row of spindles, said feeler switch having contact means located in the energizing circuit for said reversible motor and which are actuated only in the case of a misalignment as between the donner head and the next spindle to be donned.

19. Apparatus for donning empty bobbins as defined in claim 18 wherein said feeler switch includes two sets of contact means controlling respectively the operation of said motor in one direction or the other.

20. Apparatus for donning empty bobbins in succession onto a row of upright spindles on a textile processing machine comprising a support structure mountable on said textile machine for movement longitudinally along the row of spindles, a donner unit including a pivotally mounted head from which empty bobbins are donned onto the spindles, means mounting said donner unit on said support structure for movement thereof towards and away from said row of spindles, reversible drive means including a reversible motor and a feeler switch carried by said donner head and located in the line of travel along the row of spindles, said feeler switch having contact means located in the energizing circuit for said reversible motor and which are actuated only in the case of a misalignment as between said donner head and the next spindle to be donned, said donner head also including an inclined cam plate engageable by the top end of

the spindle to rock the head upwardly to enable the butt end of a bobbin held by the head to descend over the top of the spindle as said cam plate leaves the spindle and the donner head lowers.

21. Apparatus for donning empty bobbins in succession onto a row of upright spindles on a textile processing machine comprising a support structure mountable on said textile machine for movement longitudinally along the row of spindles, and a donner unit on said support structure including a pivotally mounted donner head from which empty bobbins are donned in succession onto the spindles, said donner head including an inclined cam plate engageable by the top end of each spindle for rocking said head upwardly as the head moves towards the spindle to enable the butt end of a bobbin held by said head to descend over the top of the spindle as said cam plate leaves the spindle and said donner head lowers.

22. Apparatus for donning empty bobbins in succession onto a row of upright spindles on a textile processing machine comprising a support structure mountable on said textile machine for movement longitudinally along the row of spindles, a donner unit on said support structure including a pivotally mounted donner head from which empty bobbins are donned onto the spindles, said donner head including an inclined cam plate engageable by the top end of the spindle to rock said head upwardly as the head moves towards the spindle to enable the butt end of a bobbin held by said head to descend over the top of the spindle as said cam plate leaves the spindle and said donner head lowers, and guide means positioned at the bobbin discharge side of said donner head engageable with each bobbin as it leaves said donner head for maintaining the bobbin in a substantially vertical attitude and guiding the same downwardly upon the spindle.

23. Apparatus for donning empty bobbins in succession onto a row of upright spindles on a textile processing machine comprising a support structure mountable on said textile machine for movement longitudinally along the row of spindles, a donner unit on said support structure including a head from which empty bobbins are released and donned onto the spindles, an endless conveyor having individual bobbin compartments thereon, a magazine having a plurality of bobbin feed channels arranged in side-by-side relation at the side of said conveyor for transferring bobbins from the magazine to said conveyor, a pusher arm in each channel, spring means for loading said pusher arms into engagement with the bobbins in the respective channels, and means operated periodically for transferring bobbins from the discharge end of said conveyor to said donner head to replace the bobbins as they are released in succession from said donner head.

24. Apparatus for donning empty bobbins as defined in claim 23 and which further includes means for progressively varying the loading force applied by said spring means on said pusher arms, said loading force being a minimum when said pusher arms occupy an upper substantially horizontal position at the inlet end of the channels and a maximum when said pusher arms occupy a lower substantially vertical position at the outlet end of said channels.

25. Apparatus for donning empty bobbins as defined in claim 23 wherein said bobbin feed channels in said magazine have an arcuate configuration with a horizontal inlet and a vertical outlet and which further includes a shaft on which said pusher arms are mounted for free and independent pivotal movement, a manually actuated arm coupled to said shaft, a pair of parallel spaced lifter arms secured to said shaft, a rod extending between and secured to said lifter arms parallel to said shaft, said

rod being adapted to engage said pusher arms and rotate them from a vertical to a horizontal detented position, latching levers for holding said magazine in place on said donner unit, and means for actuating said latching levers to the release position to release said magazine upon further rotation of said manually actuated arm to a level higher than that represented by the detented position of said pusher arms.

26. Apparatus for donning empty bobbins in succession onto a row of upright spindles on a textile processing machine comprising a support structure mountable on said textile machine for movement longitudinally along the row of spindles, a donner unit mounted on said support structure including a donner head pivotally mounted on a horizontal pivot axis, said donner head holding a comparatively small number of empty bobbins in side-by-side relation and having an entrance end and a discharge end from which the bobbins are released in succession and donned onto the spindles, a magazine on said support structure for storing a comparatively large number of empty bobbins, a conveyor adjacent said magazine onto which the bobbins are delivered from said magazine for movement toward the entrance end of said donner head, and means for transferring bobbins one-by-one from said conveyor into the entrance end of said donor head as the bobbins are discharged in the same manner from said donner head.

27. Apparatus for donning empty bobbins as defined in claim 26 wherein said conveyor includes upright parallel spaced end shafts mounting upper and lower sprockets for driving upper and lower conveyor chains and a torque motor in driving relation with one of said end shafts, and wherein said means for transferring bobbins from said conveyor comprises an upright driver shaft spaced parallel from the other end shaft of said conveyor, said driver shaft having two driver arms thereon 180° apart for transferring an empty bobbin from the discharge end of said conveyor to the entrance end of said donner head for each 180° rotation of said driver shaft, a sleeve rotatably mounted on the upper end portion of said other end shaft, said sleeve including a sprocket connected by a chain to a sprocket secured to the upper end portion of said driver shaft, a spiral spring interposed between said other end shaft and sleeve, one end of said spring being secured to said other end shaft and the other end of said spring being secured to said sleeve, and a lock-up mechanism between the lower ends of said driver shaft and said other end shaft, said lock-up mechanism including a double lobe cam secured to each shaft, the lobes on said cams being 180° apart, and a pivotally mounted cam follower plate between the cams, said cam follower plate including follower rollers thereon engageable with the lobes on said cams and operable by said driver shaft to periodically shift one of said follower rollers out of and then into locking position with the cam on said other end shaft for each 180° rotation of said driver shaft thereby to effect periodic incremental movements of said conveyor.
